UNITED STATES PATENT OFFICE.

JOSEPH P. GORDON, OF ROCKFORD, ILLINOIS.

ABDOMINAL SUPPORTER.

Application filed May 31, 1924. Serial No. 716,916.

This invention pertains in general to apparel and has more particular reference to abdominal supporters and to corsets of the abdominal supporting type.

5 One of the purposes of my invention is to provide an improved abdominal supporter so constructed that it will serve as a comfortable and satisfactory supporter in cases of corpulency and before and after 10 confinement and which is characterized by its light yet durable construction and its adjustability to practically any form.

Another purpose is to provide an abdominal supporter adapted to be worn in place 15 of a corset and especially to be worn while participating in golf and other athletics. In this respect the supporter is so constructed as to firmly but yieldingly support the body, and has none of the objectionable 20 features of the usual corset.

In furtherance of the foregoing my invention contemplates the provision, generally stated, of an abdominal and a back-supporting part each preferably but not necessarily constructed of approximately vertical stays joined by transverse strips, and side strips connecting the ends of the back-supporting portion to the ends of the abdominal-supporting portion and being attached to 25 the latter through the agency of draw strips, the connection being such as to permit the side strips to slip vertically on the draw strips to accommodate the abdominal-supporting portion to the form of the wearer, and the side strips preferably including 30 elastic elements and buckles or the equivalent, whereby to secure the desired tautness or fit of the supporter and to permit the desired flexibility and expansion to conform 35 to body movements. The quick adaptation 40 of this supporter to almost any form will be readily apparent from the description hereinafter.

Other objects and attendant advantages 45 will be appreciated by those skilled in this art as the invention becomes better understood by reference to the following description when considered in connection with the accompanying drawings, in which—

50 Figure 1, is a front view of the abdominal-supporting portion of the supporter;

Fig. 2, is an enlarged detail section taken on the line 2—2 of Fig. 1;

Fig. 3, is a back view of the back-supporting portion of the supporter;

Fig. 4, is a front view of a modified form of the abdominal-supporting portion;

Fig. 5, is a front view of still another modified form of the abdominal-supporting portion;

Fig. 6, is a rear view of a modified form of the back-supporting portion; and

Figs. 7 and 8, are front and edge views respectively of a spring buckle used with my improvements.

Referring to Fig. 1 it will be observed that the abdominal-supporting portion is formed of a plurality of approximately vertical stays 9, fabric covered, joined by transverse upper, lower and intermediate strips 70 11, 12 and 13, respectively. To each end of the abdominal-supporting portion is attached a draw strip shaped so as to provide a triangular end portion to the apex of which is attached a side strip which connects to the back portion as will be presently described. The location of this apex or the point of attachment of each side strip to the end portion of the abdominal-support 75 is shiftable vertically with respect to the support proper in order to accommodate the latter to different degrees of corpulency and to hold said support firmly in position under such different conditions. In the preferred embodiment of my invention the side 80 strips which give the major support and in this instance the sole support to the front and back portions by reason of their position on the wearer just above the hips, attach to said end portions of the abdominal-supporting portion so as to slip vertically thereon when positioning the supporter on a wearer. By reason of this construction the lines of pull on the abdominal-supporting portion will be centralized with respect 85 to the resistance and in accordance to the fitting of said supporting portion to the form. In the preferred embodiment this result is attained by making said end draw portions of strips 14 turned medially upon themselves into angular relation and attached at their ends to the upper and lower

strips 11 and 12. Said end strips 14 may be a continuation of either or both of said upper and lower strips. The intermediate strip 13 is extended at each end and sewed to the adjacent lower member of each end strip 14, thus reenforcing each end portion. The several strips making up the abdominal-supporting portion are preferably of non-elastic fabric.

10 The back-supporting portion, one embodiment of which is shown in Fig. 3, may be of any suitable construction and preferably of approximately vertical stays 15 joined by upper and lower strips 16 and 17 respectively which are preferably arranged so as to provide triangular end portions so as to provide a centralized attachment point at each end. To each end of the back-supporting portion is attached a side strip 18 preferably in the form of a non-elastic fabric but including an elastic element as will be presently described. Each side strip 18 may be suitably attached to the adjacent end of the back-supporting portion as through the agency of a wire loop 19 through which the end strips of said portion are passed.

My invention contemplates the provision for lengthwise adjustment of each side strip 18 to accommodate different dimensions of waist band and to draw the front and back-supporting portions to the desired tension and including also an elastic element or provision for a certain degree of elasticity so as to yield in accordance with respiratory and other body movements. This is accomplished in a simple and practical manner by the provision of a spring buckle for each side strip, which buckle also serves to establish a slip connection with the adjacent end draw strips 14. The construction of such spring buckle is best shown in Figs. 7 and 8 from which it will be seen that the body 21 of the buckle is formed of a series of convolutions of wire, one end 22 of which is shaped to provide a hook and the opposite end 23 to provide a loop through which the medial portion or apex of the adjacent end strip 14 passes. It will be manifest viewing Fig. 1 that each side strip 18 which is perforated as a belt may be passed lengthwise through the body portion 21 of the adjacent buckle and connected to the hook end 22 thereof in any one of the perforations. The lengthwise adjustment of each side strip is thus obtained through the buckle connection, the elasticity or resiliency through the spring buckle, and the adjustability as to the line of pull or distribution of the supporting pressure by shifting the spring buckle through slipping it vertically upon and with respect to its end strip 14 as noted by the dotted line positions at the left hand end of Fig. 1. While I prefer to employ spring buckles 21 in the manner dis-

closed because of the various functions performed, it should be understood that my invention contemplates broadly the provision of any suitable expedients for obtaining the lengthwise adjustment and elasticity and also for permitting the desired adjustability with respect to the point of attachment of each side strip to the adjacent end of the abdominal-supporting portion.

In Fig. 4 I have shown a modified form of abdominal-supporting portion embodying my invention, in which the vertically disposed stays 24 are longer and a pair of end draw strips are provided at each end of said portion. In this form the stays are joined by a suitable number of transverse strips 25 certain of which may be continued to form the end draw strips as shown. The upper and lower end draw strips 26 and 27 respectively are substantially the same in construction and function as the end draw strip 14 above described, and to each of these ends is attached a spring buckle 28. An abdominal-supporting portion of this type is required where greater support is necessary, but the principles of construction and advantages thereof are substantially the same as embodied in the more simple form of the invention disclosed in Figs. 1 and 3. The back-supporting portion to be worn with the abdominal-supporting portion shown in Fig. 4 has an upper and a lower side strip attached to each end for connection to the upper and lower spring buckles 28. A form of back-supporting portion suitable to this end is shown in Fig. 6 comprising vertical stays 29 joined by transverse strips 31 which in this instance form upper and lower triangular end portions 32 and 33 respectively to which the upper and lower side strips 34 and 35 are attached; these side strips being perforated and adapted for connection to the spring buckles 28 in the same manner as the side strips 18 are adapted for connection to the spring buckles 21. Inasmuch as a support of this size and shape is usually worn mainly in cases of corpulence, one or more side pads 36 may be suitably supported on either one or both of the side strips 34 and 35.

In Fig. 5 I have shown still another modification of the abdominal-supporting portion which comprises approximately vertical stays 37 joined by upper, lower and intermediate transverse strips 38, 39 and 41, end draw strips 42 and a non-adjustable lower end draw strip 43. A spring buckle 44 is attached to each adjustable end draw strip 42 and a spring buckle 45 is attached to each non-adjustable end draw strip 43. This form of supporter may be used with upper and lower side strips such as applied with a back-supporting portion of the type shown in Fig. 6.

Any one of the three embodiments of the

invention disclosed herein may be used in place of the usual corset and likewise for the purpose of an abdominal supporter. The forms shown in Figs. 1 and 5 are especially designed as a substitute for corsets. These forms are particularly well suited to be worn for golfing and while participating in other athletics, while the form shown in Fig. 4 is designed more particularly for cases of corpulence and other instances where greater support is required.

It will be manifested to those skilled in this art that in any form of the invention the abdominal-supporting portion is self-adjustable to accommodate variations in different forms and is further adjustable by means of the buckles for waist dimensions. These abdominal supporters may be worn by both men and women and when used in place of the usual corset suitable garter supports may be attached.

It is believed that the foregoing conveys a clear understanding of the objects and principles of my invention and it will be manifest from the different embodiments disclosed that considerable change might be made in the construction and arrangement without departing from the spirit and scope of the invention as expressed in the appended claims, in which—

I claim:

1. An abdominal supporter comprising an abdominal-supporting portion, a back-supporting portion, a spring buckle attached to each end of the abdominal-supporting portion, and a side strip attached to each end of the back-supporting portion and adapted to be worn over the hips and to be connected to said spring buckles, each spring buckle being vertically adjustable upon and with respect to the abdominal-supporting portion.

2. An abdominal supporter comprising an abdominal-supporting portion formed of approximately vertical stays joined by strips of non-elastic material and having at each end a strip providing a loop, a back-supporting portion, and a lengthwise adjustable connection between each end of the back-supporting portion and the adjacent loop including a part through which the loop passes and which is vertically adjustable upon and with respect to the loop.

3. An abdominal supporting type of corset comprising an abdominal-supporting portion formed of approximately vertical stays connected by strips and having at each end a buckle-carrying strip, a spring buckle attached to each end strip so as to be vertically adjustable thereon, a back-supporting portion, and side strips connected to the back-supporting portion and having perforated ends adapted to be passed through the buckles and connected thereto.

4. An abdominal-supporter comprising

an abdominal-supporting portion terminating at each end in a draw strip fastened at its ends at upper and lower points thereon, a spring buckle attached to each draw strip so as to slip vertically thereon, and a back-embracing portion having side strips adapted for connection to said buckles.

5. An abdominal supporting type of corset comprising an abdominal and a back-supporting portion each formed of approximately vertical stays joined by transverse strips, the abdominal-supporting portion having at each end a draw strip, and lengthwise extensible means including a side strip attached to each end of the back-supporting portion and connected to the adjacent draw strips so as to slip vertically thereon.

6. An abdominal supporting type of corset comprising an abdominal and a back-supporting portion each formed of approximately vertical stays joined by a fabric body, the abdominal-supporting portion having at each end a draw strip, and lengthwise adjustable means including a side strip attached to each end of the back-supporting portion and connected to the adjacent draw strips so as to slip vertically thereon.

7. An abdominal supporting type of corset comprising an abdominal and a back-supporting portion, a draw strip for each end of the abdominal-supporting portion attached at its ends at an upper and a lower point thereon, and a lengthwise adjustable connection between each end of the back-supporting portion the adjacent draw strip connected to the latter so as to slip vertically thereon.

8. An abdominal supporting type of corset comprising an abdominal and a back-supporting portion, a draw strip for each end of the abdominal-supporting portion attached at its ends at an upper and a lower point thereon, and a lengthwise adjustable connection between each end of the back-supporting portion and the adjacent draw strip connected to the latter so as to slip vertically thereon and including a resilient element.

9. In combination, an abdominal and a back-supporting portion, the former having a triangular draw strip at each end and the latter having a side strip at each end connected to the apex of each draw strip and vertically adjustable thereon.

10. In combination, an abdominal and a back-supporting portion, the former having a triangular draw strip at each end and the latter having a side strip at each end connected to the apex of each draw strip and vertically adjustable thereon, the connection between each side strip and its draw strip being established by a slip connection.

11. In combination, an abdominal and a back-supporting portion, the former having a triangular draw strip at each end and the latter having a side strip at each end con-

nected to the apex of each draw strip and vertically adjustable thereon, the connection between each side strip and its draw strip being established by a slip connection provided by a spring buckle.

12. An abdominal supporter comprising an abdominal-supporting portion terminating at each end in a triangular strip, and a back-embracing portion having ends con-

nected to said draw strips, each through the agency of spring buckles, each of which has a spring body, a looped end through which the draw strip passes and a hooked end adjustable in any of a series of perforations in the end of the back-embracing portion.

JOSEPH P. GORDON.
